PROCESS FOR MAKING OIL GAS

Charles Rosier, New York, N. Y.

Application May 26, 1926. Serial No. 111,675

2 Claims. (CL. 48—212)

This invention relates to an art or process for producing highly combustible gaseous fuel from hydrocarbon oils and steam or air for use in internal combustion engines, steam boilers, tempering furnaces, and the like.

One object of the invention is the provision of an improved process of the character described for converting fluids such as liquid fuels, and steam or air into a highly combustible oil gas.

Another object of the invention is the provision of an improved process of the character described for volatilizing a liquid fuel and separately pre-heating the fuel constituents whereby they may be readily combined to form a highly combustible gaseous product.

Another object of the invention is to provide an improved process of the character described which is easily and simply carried out to supply gas consumers, operating under various conditions and loads, with a highly combustible gaseous fuel.

A further object of the invention is to provide in an improved process of the character described, novel means having a catalytic action for gasifying hydrocarbon fuel oil, which is effective to substantially eliminate carbon or other distillate residues.

Other objects of this invention will in part be obvious and in part hereinafter pointed out.

Certain features herein shown and described, are shown, described and claimed in my co-pending application Serial No. 585,337 filed August 31, 1922 and accordingly are not claimed herein.

With the above exception, the invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a diagrammatic view in elevation of a system for supplying gaseous fuel to an internal combustion engine embodying the invention.

Fig. 2 is an elevational view in vertical section of the improved oil gasifying apparatus shown in Fig. 1, portions thereof being broken away to expose the interior construction;

Fig. 2a is a fragmentary cross-sectional, elevational view showing a modified construction of the fuel gasifying apparatus;

Fig. 3 is a cross-sectional view taken on lines 3—3 in Fig. 2; and

Fig. 4 is a fragmentary elevational sectional view of the improved apparatus shown applied to a furnace wall.

Referring in detail to the drawing, 10 denotes a fragmentary portion of any form of gaseous fuel consuming means, such as an internal combustion engine having an intake pipe 10a to which is attached the improved oil gasifying device 11.

The device 11 as seen from Fig. 2 comprises a mixing, atomizing and dispensing portion 13 connected to the pipe 10a and an oil gasifying and fuel constituent preheating portion 14 disposed therebelow, the inlet end of the portion 13 communicating with a portion 14 through a passage 15.

The portion 14 comprises a tubular member 16 having an inner chamber divided by a central tubular baffle 19 into two compartments 17 and 18 of semiannular cross-sectional shape, said baffle having outwardly extending partition portions 19a, the baffle and partition portions being disposed to extend longitudinally through said member 16 as shown in Figs. 2 and 3. The lower compartment 17 is adapted to receive liquid fuel, such as a hydrocarbon oil at the front end 20 thereof through nipple 21 which connects with the outlet side of a liquid fuel control valve 22.

The inlet side of said valve 22 receives fuel preferably under pressure through a pipe 25 supplied by a suitable feed pump 23 from a fuel storage tank 24. The valve 22 is operated in the well understood manner by rotating the valve stem 22a. Suitable means, such as a discharge pipe,

26 for draining the lower compartment 17 into the tank 24 is provided, said means being operated by a suitable valve or cock 28.

In the lower compartment 17, the liquid fuel supplied thereto is adapted to be vaporized, initially expanded and subjected to the catalytic action in the manner as will hereinafter appear. The upper compartment 18 which communicates with the lower compartment 17 through the passages 19b serves to gasify and preheat the vaporized expanded fuel and is provided at its upper front end 18a with the upwardly extending passage 15 for leading the oil gas into the inlet side of a control and mixing valve 29 from which they emerge through an aperture 30 into a mixing chamber 31. The valve 29 controls the flow of the oil gas in the usual manner through rotation of the valve stem 29a. To form a more efficient gaseous fuel and for conditioning the oil gas generated in the portions 14, suitable amounts of a gaseous fuel constituent or medium, such as steam or compressed air are 110

supplied through a pipe 32 into an annular passage 29b formed in said valve 29, said passage having openings 29c through which the steam or air is injected into the chamber 31 so that an intimate mixture of the gasified oil and steam or air is obtained. Where compressed air is used as the medium, an installation as shown in Fig. 1 may be employed. Here the air is supplied by a suitable compressor 33 to a supply tank 34, hence through a pipe 35 to an inlet 36a adjacent the rear end of a jacket 36 which surrounds the chamber compartments 17 and 18 in portion 14 as is clearly shown in Fig. 2. For controlling the flow of air through the jacket 36, a valve 37 is installed in the pipe line 35, the front or outlet 36b of the jacket being connected directly with the pipe 32 for supplying air to the valve 29.

For preheating and gasifying the fuel constituents passing through the portion 14 and chamber 36, any suitable heat source may be provided, preferably, as here shown, an electrically operated heater 40. Said heater is constructed to fit into a longitudinally extending pocket 14a in portion 14 for heating the inner jacket wall 36c and the walls 17a, 17b, and 18a, 18b of the chamber compartment 17 and 18. The jacket wall 36c is spaced from the wall 17a and 18a to permit the extension therethrough of a plurality of heat resistant elements 41 of heater 40. Said elements are supported at each end by a suitable terminal member 42 which is mounted on an insulating base 43, the latter forming a closure for the pocket 14a, as is clearly shown in Figs. 2 and 3. Suitable binding posts 44 may be provided to extend through said base for connecting said heater elements 41 in series with a suitable control rheostat 45 across a suitable electric power source (not shown) through conductor wires 46.

It is clear from the drawing that the heater 40 when connected to the electric power source is effective to supply the initial heat to the gasifying apparatus 11 for raising it to the required temperature to gasify and preheat the fuel constituents. The heater 40 may be operated to positively control the temperatures to which the liquid and vaporized oil in compartments 17 and 18 are subjected during the gasifying and preheating process simultaneously with the preheating of the air in the jacket 36 simply by adjusting the rheostat 45 to regulate the power supply.

One dominant feature of the invention resides in the provision of the baffle 19 which may be made of any suitable material having catalytic properties when heated, such as nickel, platinum, palladium, copper, brass or other like substances. As shown in Fig. 2, the baffle 19 is in the form of a cylindrical tubular structure, one end thereof abutting the front wall 14b of the portion 14 and the other end thereof being supported by the rear end wall 16a of the tubular member 16. The rear end of the axial passage 19c extending through the baffle communicates with the pocket 14a adjacent said wall 16a thereby providing a relatively large heating surface for the baffle exposed to heat from the heater 40 whereby the catalytic effectiveness of said baffle is greatly increased.

In Fig. 2a is shown a modified form of the invention in which a supplementary electric heater 140 having terminal post 144 is provided, said posts being preferably connected in series with a rheostat 145 to a suitable power source (not shown) by conductor wires 146. Said heater

extends through the rear end wall 14c of the portion 14 and into the axial passage 19c of the baffle 19 for independently controlling the temperature and the catalyzing effect of said baffle.

The normal operation of the equipment above described is as follows: Liquid fuel is fed under pressure through the valve 22 into the gasifying apparatus 11 where it is vaporized, expanded and subjected to catalytic action in the compartment 17, the gases therefrom being preheated further expanded and catalyzed in the compartment 18. The heated gasified fuel passes from the compartment 18 through the passage 15 and the valve 29 into the chamber 31 where they are intimately mixed with the heated compressed air coming through the pipe 32 from the jacket 36, prior to passing through distributing passages 39a of an elongated nozzle 39 which extends into the intake pipe 10a as shown in Fig. 2.

The equipment described above may have a tendency to operate irregularly especially under fluctuating load of the fuel consumer. This undesirable tendency is apparently due to the building up of a back pressure during the vaporization and expansion of the liquid fuel in compartments 17 greater than the normal pressure of the liquid fuel being fed by the pump 23. To overcome this undesirable tendency, a device R for automatically regulating the feeding of the liquid fuel is provided. Said device may be inserted in any convenient location in the feed pipe line 25, or as shown in Fig. 2 may be incorporated to form a part of the valve 22. Said device R is seen to include a vertically slidable member 60 having a valve disc 61 mounted on its upper end thereof, said disc being adapted to raise against a seat 62 for shutting off the back flow of the liquid fuel due to any sudden fluctuation of load or for any other cause which is effective to increase the pressure of the gas in the compartment 17 above the feeding pressure of the liquid in the pipe 25. Normally, the disc 62 is in the position shown in Fig. 2 which permits the flow of liquid fuel around the slidable member 60 and into the body of the valve 22.

The improved process for forming a heated highly combustible gaseous fuel from a hydrocarbon oil and air is thus seen to be a result of gasifying the oil, preheating same, and while in this preheated gaseous state, combining it with the heated air under pressure without appreciably lowering the temperature of the mixture and further subjecting the oil during the gasifying process to a catalytic action which is effective to eliminate deposits of carbon residues in the compartments 17 and 18. This process is easily and simply carried out by controlling the heating of the gasifying apparatus 11 and the valves 22, 29 and 37. The radiation heat losses may be greatly diminished by making the pipe 32 as short as possible and providing suitable heat insulating laggings or coverings 65, 66, and 67 over the exterior surface of the apparatus 11, pipe 32 and intake 10a, respectively. In Fig. 4 is shown an apparatus applied to a furnace wall W. Here, the nozzle 39 is replaced by a burner nozzle 139, the latter being mounted in position in any suitable manner by a frame 70, orifices 70a being provided in said frame 70 for admitting air from the outside. The air passing through said orifice may be regulated in any suitable manner for supplying any excess air that may be needed during the operation of the burner, as by means of a ring or sleeve 71 having opening 71a which ring may be operated to close the orifices 70a.

It will be noted that the hydrocarbon oil is merely vaporized and expanded but is not cracked or broken down, due to the temperature control preventing such reaction, the gasified oil being furthermore intimately mixed with the gaseous fuel constituent without application of additional heating, thus preventing reaction with the gaseous constituent.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. The art of preparing a gaseous highly combustible fuel from liquid and gaseous fuel con-

stituents consisting in applying heat to each of the constituents for vaporizing, expanding, and gasifying the liquid constituents and preheating the gaseous constituent, separately subjecting the liquid constituent to a catalytic action during vaporization and then mixing said constituents while in a heated state to form a highly combustible fuel.

2. The art of producing gaseous fuel from liquid and gaseous fuel constituents consisting in separately gasifying the liquid constituent in the presence of a catalyzing agency applying heat thereto, preheating the gaseous constituent by applying a different source of heat, regulating the intensities of both sources of heat for controlling the gasification, catalytic activity, and the preheating of the gaseous constituent to bring said constituents to a desired condition, and injecting the preheated constituent into the gasified constituent in proper proportion to form a gaseous, highly combustible product.
